(57) **CLAIM**

The ornamental design for a bucket for dehumidifier, as shown and described.

DESCRIPTION

FIG. 1 is a perspective view of a bucket for dehumidifier, showing our new design;
FIG. 2 is a front view thereof;
FIG. 3 is a rear view thereof;
FIG. 4 is a side view thereof;
FIG. 5 is another side view thereof;
FIG. 6 is a top view thereof;
FIG. 7 is a bottom view thereof; and,
FIG. 8 is an exploded perspective view of a dehumidifier showing the bucket in an environment of use.
The broken lines illustrating portions of a bucket for dehumidifier form no part of the claimed design. The broken lines illustrating portions of a dehumidifier in FIG. 8 are environmental purposes only and form no part of the claimed design.
